CLAIM

The ornamental design for a beer bottle ornament, as shown and described.

DESCRIPTION

FIG. 1 is a front perspective view of my new design for a beer bottle ornament, the beer bottle and cover shown in phantom lines being for illustrative purposes only and forming no part of the claimed design;

FIG. 2 is a right side elevational view thereof, the beer bottle shown in phantom lines being for illustrative purposes only and forming no part of the claimed design, and the left side elevational view being a mirror image of the right side elevational view;

FIG. 3 is a front elevational view thereof;

FIG. 4 is a top plan view thereof;

FIG. 5 is a rear elevational view thereof; and,

FIG. 6 is a bottom plan view thereof.
